[57] CLAIM

The ornamental design for a key chain connector ring, as shown and described.

DESCRIPTION

FIG. 1 is a perspective view of a key chain connector ring showing my new design;

FIG. 2 is a front elevational view;

FIG. 3 is a side elevational view;

FIG. 4 is a rear elevational view;

FIG. 5 is a side elevational view of the side opposite FIG. 3;

FIG. 6 is a top plan view; and,

FIG. 7 is a bottom plan view.

The broken line showing of a housing is for illustrative purposes only and forms no part of the claimed design.
